UNITED STATES PATENT OFFICE.

MOSES DUBINSKY, MAX J. NATHAN, AND MOSES EISENBERG, OF PHILADELPHIA, PENNSYLVANIA.

DESIGN FOR A HOOD.

SPECIFICATION forming part of **Design No. 25,849**, dated July 28, 1896.

Application filed April 10, 1896. Serial No. 587,031. Term of patent 7 years.

To all whom it may concern:

Be it known that we, MOSES DUBINSKY and MAX J. NATHAN, citizens of the United States, and MOSES EISENBERG, a subject of the Czar 5 of Russia, all residing in the city and county of Philadelphia, State of Pennsylvania, have invented and produced a new and original Design for a Hood, of which the following is a specification, reference being had to the accompanying drawing, forming part thereof.

The leading feature of our design for a hood, consisting of a cap, a cape, and crossed tabs, is the shoulder portions of said cape, extending laterally outwardly from the base of the 15 body of the cap and joining the widened top of said tabs.

The figure represents a front view of a hood embodying our design.

In the drawing, A designates the head portion of the hood, the same being somewhat of the form of the body of a cap. Depending from said portion is a cape, consisting of the skirt B at the base of the body of the cap, the flaring neck and shoulder portions C C',

and the crossed tabs D, which have their lower 25 ends extended laterally at E' E' and continued from the extension E' E' downwardly therefrom, as at F F.

At the front of the hood, within the base of the head portion, forward of the skirt B and 30 the neck and shoulder portions C, and above the tabs D, is an opening E, across the lower part of which is the closing-flap F, which extends from the top of one tab to the other.

The shoulder portions C extend laterally 35 outwardly from the base of the skirt or body of the cap, and the tops of the tabs are widened to form continuities of said laterally-extending shoulder portions.

What we claim is—

The design for a hood, substantially as described and shown.

MOSES DUBINSKY.
MAX J. NATHAN.
MOSES EISENBERG.
